US00D461797S

(12) **United States Design Patent** (10) Patent No.: **US D461,797 S**
 Sumer et al. (45) Date of Patent: **** Aug. 20, 2002**

(54) **HOUSING FOR TELECOMMUNICATIONS MODULE**

(75) Inventors: **Suleyman Oguz Sumer**, Raleigh; **James Edward Bartlett**, Cary; **Brian Donald Van Voorhis**, Wake Forest, all of NC (US)

(73) Assignee: **ADC DSL Systems, Inc.**, Eden Prairie, MN (US)

(**) Term: **14 Years**

(21) Appl. No.: **29/149,535**

(22) Filed: **Oct. 10, 2001**

(51) LOC (7) Cl. **14-03**

(52) U.S. Cl. **D14/240**

(58) Field of Search **D14/137, 240, D14/138, 242, 308, 356, 357, 358, 311, 313, 441, 144, 348-355, 370, 341-347, 125, 432, 433, 155, 299, 257, 439, 140, 188, 230, 241, 243, 245; 379/433.01-433.13, 419, 434, 428.01-428.04, 420.01-420.04, 440, 441, 442; 455/550-575, 90; D13/184, 123, 152, 147, 110**

(57) **CLAIM**

The ornamental design for a housing for telecommunications module, as shown and described.

DESCRIPTION

FIG. 1 is a front perspective view of a housing incorporating a design according to the invention.

FIG. 2 is a front view of the housing of FIG. 1.

FIG. 3 is a left side view of the housing of FIG. 1.

FIG. 4 is a right side view of the housing of FIG. 1.

FIG. 5 is a top view of the housing of FIG. 1; and,

FIG. 6 is a bottom view of the housing of FIG. 1.

1 Claim, 3 Drawing Sheets

FIG. 2

FIG. 4

FIG. 2

FIG. 3

FIG. 5

FIG. 6
